COPYING DEVICE

William C. Bohmert, Mamaroneck, N. Y.

Application February 12, 1930, Serial No. 427,818
Renewed September 6, 1933

4 Claims. (Cl. 197—126)

This invention relates to copying devices and more particularly to such devices adapted to use on typewriters.

The objects of the invention are, among others, 5 to provide a copying device that can be quickly attached to and detached from the platen of a typewriter, that produces a reverse impression on the back of a transparent copying sheet, that is low in cost and, although adapted for discard 10 when detached from the platen still possesses such great copying longevity as to effect an appreciable economy in typewriter manifolding, that is quickly installed on the platen without smudging of the copying material and without 15 smearing the fingers of the operator, that does not smear the side rolls or guides of the typewriter when installed, that enhances the endurance of the platen surface, and that possesses novel features of construction and relationship 20 of the component elements providing the foregoing properties in the article and also anticipating low manufacturing cost.

I am well aware that inventors have essayed contributions to the field of reverse copying upon 25 a transparent copying sheet in a typewriter. The essential elements of low cost and adaptability for quick insertion and removal from the copying position have heretofore been lacking.

Reference is made to the drawing which is a 30 part of this specification, in which

Figure 1 is a perspective view from the right front of my copying device but with parts slightly opening up from normal position to show the construction more clearly,

Figure 2 is a right end view with the elements also opened up as in Figure 1,

Figure 3 is a front view with the diametric scale reduced one-half, and

Fig. 4 is an end view showing the angular 40 bend in the strip 5 when in operative position on the platen of a typewriter.

Referring to the drawing for a view of the present embodiment of my invention, it is observed that my device is constructed in the 45 form of a cylinder whose inner circumference is approximately the same as that of the circumference of a typewriter platen. Where there is variation in the sizes of platens the only change required to make my invention adaptable 50 to such typewriters is to make the measurements of the components of my copying device conform with the circumference of the particular platen or machine model platen on which my device is to be used. In installing the device 55 it is simply necessary to remove one or two

screws from the typewriter, lift the roll off the machine and then slip the cylindrical copying device over the end and into central position. Only one removal of the platen is required, it is obvious, both to remove a used device and to 60 insert a new one. The numerals 1 and 2 indicate in all the views the overlying edge and the underlying edge respectively of a thin sheet impregnated with carbon or copying ink of a type that produces a maximum of copies adapted 65 for making a reverse impression upon the back of a transparent overlying copying sheet. It is noted in Figures 1 and 2 that the terminating edge 1 overlies the edge 2 in a counterclockwise direction as viewed from the right so that as the 70 copying device is rolled through the platen support of a typewriter any inadvertently unsecured part would not be torn or turned by the feed rolls to produce a copy blank and thereby render the whole device useless. It will be noted later 75 that I provide indices to insure the insertion of the copying device so that the foregoing condition always obtains.

After experimenting with a great number of materials I have selected a 40-lb. Kraft paper 80 which I cut in sheets that are approximately the width of the platen and whose length is twice the circumference of the platen cylinder for which they are manufactured, or a multiple of this measurement. The top edge 4 is then rolled 85 under and after two turns the sheet terminates in the same radial plane 6 in the opposite edges with a whole or continuous strip 5 inbetween. As shown in Figures 1 and 2 the top layer 3 is shown for the sake of illustration slightly bent 90 away from the strip 5 and similarly the lower layer 4 but in the completed tube as shown in Figure 3 the parts 3, 4, and 5 are snugly compressed together. The 40-lb. Kraft paper is tough and stiff but yet sufficiently flexible to form 95 a slight bend or angle from left to right as viewed from the right permitting the top layer 3 terminating in the radial plane 6 of the cylinder to lie snug against one side of the bend in strip 5 and the terminal end of lower lever 4 to lie snug 100 against the opposite side of the bend lying in-between in part 5 lying inbetween. It is noted in Figures 1 and 2 as viewed from the right that the terminal edge of the top layer 3 is in a direction counterclockwise and in the same direction 105 as the terminal edge 1 of the copying surface so that in its normal operation position the edge of part 3 in plane 6 is always to the rear as passed through a typewriter in operation so that the feed rolls tend to press it toward the part 5 110

and to hold the edge snug against the angled surface of 5 between the top edge and the bottom edge in the radial plane 6. By this construction of my device I provide a stiff and durable supporting cylindrical base for my copying surface without having a longitudinal surface ridge which if present would tend to tear or break the thin copying surface or to blank the copy by the incidence of the typewriter type upon a line in which there was no backing surface. By the construction above described in practice there is no edge of sufficient prominence to affect the production of a clear copy or to cause any breaking or tearing of the copying surface. By reference to Figures 1 and 2 it is also clear that the juncture longitudinal line of terminal edges 1 and 2 of the copying sheet is circumferentially removed from the radial plane 6. As shown in Figures 1 and 3 I provide as indices in inserting my copying device on the typewriter platen in such a position as to get the beneficial results of my construction in the fullest degree as above set forth the word "Right" imprinted on the exposed side strip 7 of the surface 3. As shown in Figure 3 there is another strip 7 on the opposite side provided by cutting the carbon or copying sheet of less width than the sheet 5 and centering the carbon or copying sheet on the sheet 5. These strips 7 are of sufficient width to provide a noncopying surface by which the copying device may be picked up in the fingers without smearing them with the copying material and also they prevent the copying material from smudging the side guides or rolls of the typewriter a condition which would practically inhibit the use of my device. The component elements of my device are preferably secured together by a good adhesive material.

The longevity of my device has been proven to be many multiples of the period of longevity of a carbon sheet and therefore my invention effects, besides a great saving in the time of the operative, also a considerable economy in the cost of materials used. This economy is also augmented by an increase in the life of the platen surface of the typewriter. My stiff backing surface absorbs the usual row of indentations in the rubber platen and after using many of my devices the platen surface shows no sign of use at all.

In order to facilitate the removal of a used tube from the platen I provide a notch or cut away portion 8 in the upper of the two layers of the paper for the easy insertion of a knife-blade or point or other instrument for cutting or ripping the tube lengthwise, preferably at the end of a longitudinal line free of the adhesive or gum used to secure the two portions of paper together.

75

Having now particularly described and pointed out the construction and use of a preferred embodiment of my invention I do not choose to limit myself except as in the appended claims.

I claim:—

1. As an article of manufacture, a copying device adapted to overlie a typewriter platen and to produce a reverse impression of typed matter on the reverse side of a copying sheet, comprising a sheet of stiff fibrous material sufficiently heavy to support a large number of type impacts, made into a cylinder and said sheet having a length slightly less than twice the circumference of the platen, or a multiple thereof whereby the end edges will not overlap to form a bulge or ridge across the cylinder, and a copying material superimposed thereon. 80

2. As an article of manufacture, a copying device adapted to overlie a typewriter platen and to produce a reverse impression of typed matter on the reverse side of a copying sheet, comprising a sheet of stiff fibrous material sufficiently heavy to support a large number of type impacts, made into a cylinder and said sheet having a length slightly less than twice the circumference of the platen, or a multiple thereof whereby the end edges will not overlap to form a bulge or ridge across the cylinder, and a copying sheet having a length slightly greater than that of the circumference of the platen secured 90 to said cylinder. 95

3. As an article of manufacture, a quick detachable copying tube adapted to snugly fit and cover a typewriter platen and adapted to produce a reverse impression of typed material on the back of a copying sheet, comprising a cylinder formed of two plies of stiff pliable paper the end edges of the inner and outer plies terminating a slight distance apart circumferentially of the cylinder whereby that part lying intermediate 100 the end edges will be bent across the end edge of the inner ply to provide a recess into which the end edge of the outer ply will seat. 110

4. As an article of manufacture, a quick detachable copying tube adapted to snugly fit and cover a typewriter platen and adapted to produce a reverse impression of typed material on the back of a copying sheet, comprising a cylinder formed of two plies of stiff pliable paper the end edges of the inner and outer plies terminating 120 a slight distance apart circumferentially of the cylinder whereby that part lying intermediate 125 the end edges will be bent across the end edge of the inner ply to provide a recess into which the end edge of the outer ply will seat, and 130 a thin carbon sheet on said cylinder and overlapping on a line removed from said end edges. 135
